Primary Examiner — Lakiya G Rogers*Assistant Examiner* — Altaira J Swangin*(74) Attorney, Agent, or Firm* — Alston & Bird LLP(57) **CLAIM**

The ornamental design for a flashlight, as shown and described.

DESCRIPTION

FIG. 1 is a perspective view of a flashlight according to my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom plan view thereof.

The dash-dash broken lines showing in the views illustrate portions of the flashlight that form no part of the claimed design.
